UNITED STATES PATENT OFFICE.

GEORGE W. HAINES, OF MAINE PRAIRIE, CALIFORNIA.

IMPROVEMENT IN GANG-PLOWS.

Specification forming part of Letters Patent No. 124,571, dated March 12, 1872; antedated March 7, 1872.

SPECIFICATION.

To all whom it may concern:

Be it known that I, GEORGE W. HAINES, of Maine Prairie, in the county of Solano and State of California, have invented an Improved Gang-Plow; and do hereby declare that the following is a full and exact description of the same, reference being had to the accompanying drawing and to the letters of reference marked thereon.

The object of my invention is to provide an improvement in that class of plows known as "sulky gang-plows," and it consists, first, in an improved method of mounting the driver's seat, so that it is supported directly from the axle, thus relieving the plow-frame from much superfluous weight which has ordinarily to be raised. It further consists in a novel combination and arrangement of levers for elevating and depressing the plows and their frames; and also in an adjusting-gear, by which the plows are moved to or from the land and the axle of the wheels is made to stand at an angle with the plow-frame, so that the line of draft can be more or less altered, as in plowing curves.

Referring to the accompanying drawing, Figure 1 is a side elevation; Fig. 2, a plan; Fig. 3, a bottom view.

To enable others skilled in the art to which my invention most nearly appertains to make and use the same, I will now proceed to describe fully its construction and operation.

A A are the beams to which the plows are secured, and these extend forward over the axle sufficiently far to receive the rear end of the pole B, which is pivoted between them. The seat-standards C C' extend down on each side of the beams A, and are secured to the axle D, so that the driver's seat E, which is secured to their upper ends, is supported directly upon the axle. The furrow-wheel is made somewhat larger than the land-side wheel; and if it is necessary to still further depress the furrow-wheel for the purpose of making the driver's seat stand level, it is done by raising the standard C' and securing it, as desired, by means of a set or clamping nut, F, the bolt of which passes through a slot in the standard, as shown. The device for elevating the plows from the ground or depressing them into it con-

sists of a compound lever, constructed as follows: A shaft, G, extends across the front of the seat-standards, turning in boxes affixed to them. At the ends of this shaft levers H project forward, and are connected by links I with a cross-bar, J, on the plow-frame. This bar extends across the front ends of the beams A A, and is turned up at the ends to form suitable lugs for the attachment of the links I. At one side the lever H is continued back, forming an arm, L, which is connected with the operating foot-lever M, by means of a link, N. This lever extends behind the link to a short distance, and is pinned to the side of the frame-timber A. A curved holding-rack, O, secures the lever at any desired point. When it is desired to elevate the plows, pressure is brought upon the foot-lever M, and this, through the levers and the links I, elevates the front end of the plow-frame, which turns on the bolt that connects it with the pole, so as to stand at a small angle, and, by thus elevating the points of the plows, they will be easily drawn from the ground as the team moves on. At the same time the rear end of the lever M acts to elevate the rear end of the frame, so that the plows, once started, are easily drawn out of the ground. An opposite movement of the lever depresses the points of the plow and causes them to enter the soil. The axle has two arms, P P, secured to it near its outer ends, and these arms unite at a point, Q, beneath the pole where they are pinned to the rear end of a short lever, R. To the front end of this lever is attached a draft-rod, S, which extends along beneath the pole and terminates in a link, t, at the front. The lever R is operated by the stout pin U, which serves as its fulcrum and extends up through the pole. This pin is secured to the lever R below, and has an operating-lever, V, secured to it above the pole, so that, by simply moving the lever V to one side, the pin U turns the lever R; and by its action the arms P are so moved as to turn the axle so that it will stand at a small angle with the frame A. The front end of the lever R turns the rear end of the rod S to the opposite side from that occupied by the ends of the arms P; and thus the plows can be made to move so as to plow a curved furrow. If desired, the plow-frame A may be rigidly attached to the pole at dif-

ferent angles, by means of a pin which passes through the front cross-beam and enters the rear end of the pole.

By these different arrangements I make a plow very easy to operate, while the whole combination is extremely efficient.

Having thus described my invention, what I claim, and desire to secure by Letters Patent, is—

1. The operating device for elevating and depressing the plows, consisting of the levers M L H and the links I N, or an equivalent device, substantially as described.

2. The seat E supported directly upon the axle D, as shown, and leveled by means of the

slotted standards C and clamp-screw, as described.

3. The arms P P and the double vibrating lever R, together with the draft-rod S and the operating-lever, as described and set forth.

4. I claim a gang-plow having in combination the seat, supported as shown, together with the herein-described device for giving a vertical and a side or curving movement.

In witness whereof I have hereunto set my hand and seal.

GEORGE W. HAINES. [L. S.]
